UNITED STATES PATENT OFFICE.

LUCIUS R. RANDALL, OF ELZA, GEORGIA.

SHOVEL-PLOW.

SPECIFICATION forming part of Letters Patent No. 735,297, dated August 4, 1903.

Application filed October 16, 1902. Serial No. 127,472. (No model.)

To all whom it may concern:

Be it known that I, LUCIUS R. RANDALL, a citizen of the United States, residing at Elza, in the county of Tattnall and State of Georgia, have invented certain new and useful Improvements in Shovel-Plows; and I do hereby declare the following to be a full, clear, and exact description of the invention, such as will enable others skilled in the art to which it applies to make and use the same, reference being had to the accompanying drawings, and to the figures of reference marked thereon, which form a part of this specification.

This invention relates to shovel-plows designed particularly for cotton cultivation. Its objects are, first, to generally improve the construction and adjustment of such plows; second, to provide a novel means of attaching the sweeps to the standard; third, to improve the sweep and heel adjustment.

With these and other objects in view the invention is hereinafter described, and is illustrated in the accompanying drawings, in which—

25 Figure 1 is a side elevation of the plow. Fig. 2 is a front view of the plow-standard, the moldboard and point being removed. Fig. 3 is a sectional view of the moldboard and plow-point. Fig. 4 is a sectional view of the sweep. Fig. 5 is a vertical section of the heel, showing the spring-latch arrangement for holding the sweeps to the heel; and Fig. 6 is a top view showing the beam connections.

35 Referring specifically to the drawings, 6 indicates the beam; 7, the front standard; 7^a, the rear standard; 7^b, a brace for the rear standard, extending therefrom to the cap-piece 7^c at the top of the front standard, and 8 the 40 handles bolted to the rear standard by bolts 8^a, which pass through slots (indicated at 7^d) in the rear standard, so that the handles can be raised or lowered. On the under side of the beam is a convex bearing-plate 6^a, fitting 45 a corresponding concavity in the cap-plate 7^c, which is joined to the beam by a bolt 6^b. A joint is thus formed between the beam and the cap-plate, whereby the beam can be adjusted vertically and laterally with respect 50 to the standard. The hole through which the bolt passes is therefore enlarged, as indicated in dotted lines. The rear end of the beam

fits in a box-casting 9, which has a flange 9^a, forming a lap-joint with a vertical flange 10^a of a coupling-piece 10. The meeting faces of 55 the flanges are held together by a bolt 9^b. One of the flanges, preferably that of the coupling-piece, is slotted, as indicated in dotted lines at 10^c, to permit desired vertical movement or adjustment. 60

The coupling 10 is joined to the top of the rear standard 7^a by a bolt 10^b, and the coupling rests on a transverse horizontal shoulder 7^e, formed on the rear standard. Lateral adjustment is effected by slotting the coupling 10 horizontally, as indicated at 10^c in dotted lines, Fig. 6, the bolt 10^b passing through the slot.

The moldboard is indicated at 11, formed in one piece, and the plow-point at 12. They are 70 secured to the standard in the following manner: The lower end of the standard 7 is flanged or flattened, as at 7^f, which portion has socket-holes 7^g for lugs 11^a and 11^b and 12^a and 12^b on the back of the moldboard and plow-point, 75 respectively. The lugs 11^a and 12^a are hooked, as shown, and the hooked portions engage under the standard. The lugs 11^b and 12^b are notched, as shown, to receive the bolts 7^h of simple spring-latches (indicated at 7ⁱ) on the 80 back side of the standard. By this construction the plow-point or moldboard may be readily attached or detached and when attached are securely held in place without the use of bolts or loose parts. 85

The lower end of the standard has a branch 13^a to form a support for the heel 13, to which it is joined by a pivot-bolt 13^b. The parts are halved and lapped, and the meeting faces have radial corrugations, as indicated in 90 dotted lines. The heel carries the sweeps 14 and is adjustable vertically on the pivot-bolt to vary the height of the sweeps. The sweeps are attached to the heel by means similar to those shown for attaching the moldboard to 95 the standard—that is, the sweeps have a hooked lug 14^a, which enters a socket 13^c in the heel, and a notched lug 14^b, which enters a socket 13^d in the heel, with a spring-latch 13^e engaging the notch. The latch-bolt can 100 be depressed and withdrawn to permit removal of the sweeps.

To keep the slide of the plow level irrespective of the adjustment of the heel 13, said

heel is provided with a shoe 15, having a vertical flange 15^a and joined to the heel by a pivot-bolt 15^b, the adjustment being fixed by a bolt 15^c, which passes through a slot in 5 the flange 15^a.

By the construction shown the plow-beam can be adjusted as to side draft or to make the plow run shallow or deep. The mold-board, point, and sweep attachment is simple 10 and effective and permits quick change without tools. The sweep adjustment is useful to accommodate local conditions.

What I claim as new, and desire to secure by Letters Patent, is—

15. 1. The combination with the standard, of the heel adjustably connected thereto and

carrying sweeps, and the shoe pivoted to the heel and adjustable vertically thereunder with respect thereto.

2. The combination with the heel having 20 sockets therein, of the sweeps having lugs thereon fitting in the sockets, and a spring-latch carried by the heel and engaging a lug, substantially as and for the purpose described. 25

In testimony whereof I affix my signature in presence of two witnesses.

LUCIUS R. RANDALL.
